UNITED STATES PATENT OFFICE.

CLARENCE N. CHILDS, OF LOWELL, MASSACHUSETTS.

INSTEP-ARCH SUPPORT.

1,036,452.

Specification of Letters Patent. Patented Aug. 20, 1912.

Application filed July 31, 1911. Serial No. 641,418.

To all whom it may concern:

Be it known that I, CLARENCE N. CHILDS, of Lowell, in the county of Middlesex and the Commonwealth of Massachusetts, have 5 invented certain new and useful Improvements in Instep-Arch Supports, of which the following description and claims, with the accompanying drawing, are a specification.

10 Like numerals on the drawing denote like parts.

My invention relates to instep-arch supports for insertion in and removal from footwear for the rectification of the deformities known as "weakened foot" and "flat foot" and to that class of such supports which comprises a plate having a body portion shaped to underlie the instep-arch and a side portion that is integral with the body 20 portion and opposed to the side surface of that arch.

My invention relates more particularly to the extent of the body portion of the plate, to the means for preventing the longitudinal or, lateral movement of the support relatively to the foot, to the means for giving rigidity to the support or such resilience thereto as is suited to the pathological condition or the heaviness of the patient, and to 30 the means for cushioning the support for the comfort of the patient.

In the drawing, which shows my invention in the preferred form: Figure 1 is a plan of a form of footwear, such as a boot or shoe, with the upper removed at a horizontal section near the sole, with the metallic portion of my support inserted therein, but with the cushion omitted for greater clearness; Fig. 2 is a plan of the metallic 40 portion; Fig. 3 is a side-elevation thereof; Fig. 4 is a longitudinal section taken at the line 4-4 of Fig. 2 with a corresponding section of the cushion, in place; Figs. 5, 6, and 7 are cross-sections taken at the lines 5-5, 45 6-6, and 7-7, respectively, of Fig. 2, with a corresponding section of the cushion, in place, in each case; Fig. 8 is a plan of the cushion shown flat and before it has been curved to its place in the footwear but with 50 the metallic portion of the support in plan beneath it.

The preferred form of my invention comprises a resilient metallic plate having a body portion 1 curved to conform to the

lower surface of the foot beneath the tarsal 55 and metatarsal arches, extended forwardly to a location 2 anterior to an articulation of a metatarsal bone with its phalanx, and extended rearwardly to a location 3 posterior to the lowest part of the os calcis. Its outline at the heel 4 4 is curved to conform 60 nearly to the outline of the inner sole of the footwear at the heel. It has one or more holes 5 in its posterior part for a screw or other projection 6 from the heel of the foot- 65 wear for maintaining the support in position at the heel. The plate 1 has side portions integral with the body portion and curved to conform to the inner side portions of the tarsal and metatarsal arches. The 70 posterior side portion 7 is shaped to fit and support the inner side of the tarsal-arch. and is extended laterally and vertically from the body portion 1 only enough to give the 75 desired stiffness to the inner side of the resilient plate and to provide a sufficient side support opposite to the head of the astragalus and for the cushion or loose insole.

The anterior part 8 of the side portion of the plate is a tongue extended laterally and 80 vertically from the body portion with which it is integral and curved to fit the side surface of the foot. A part of the tongue 8 which is farther than the remainder from the body portion is more nearly vertical 85 than the remainder and is constructed to be almost fixedly located laterally relatively to the foot between the side of the foot and the upper of the footwear. To diffuse the pressure of the more nearly vertical part of the 90 tongue 8 over an area of the side of the foot which is larger than its own area thereby increasing the comfort of the wearer and reducing the possible lateral movement of the more nearly vertical part of the tongue 95 relatively to the foot, a cushion 12 of leather or other material, to be hereinafter described, intervenes between the tongue 8 and the side of the foot. This more nearly vertical part of the tongue is the part of the 100 instep-arch support from which the forward part of the body portion of the plate is laterally located, relatively to the foot. The surgeon, when fitting the plate to the foot of the patient, can bend the tongue 8 in 105 any desired direction by the aid of suitable tools. He can so bend it as to bring the forward part of the body portion of the

plate nearer to the more nearly vertical part of the tongue, or, so as to carry it farther therefrom, thus adjusting the lateral location of the forward part of the body portion 5 to the foot. Such adjustment, without a corresponding bending of the posterior part 7 of the side portion of the plate, will vary the pressure of the part 7 whereby it resists the inward movement of the scaphoid 10 and the head of the astragalus. Under some circumstances this may be advisable. The tongue 8 is a substantial tongue, that is, it is strong enough and stiff enough, throughout its whole extent, to maintain, while the 15 support is being worn, the forward part of the body portion of the plate in its position of lateral adjustment with respect to the more nearly vertical portion of the tongue; and, therefore, with respect to the foot. 20 Thus the tongue 8 is for locating, adjusting and maintaining the forward part of the plate in its lateral position relatively to the foot. The tongue 8 is located forward of the raised side 7 of the tarsal-arch support 25 and rises above its upper edge. The head of the first metatarsal bone is the only bony part of the inner side of the forward part of the foot that rests firmly and continuously upon a fixed support. This head is 30 ball-shaped and not constructed to resist the lateral pressure of the tongue 8 with comfort to the wearer. I have experimented by locating the tongue 8 in different positions lengthwise of the foot and I prefer to locate it alongside of the shaft of the first metatarsal bone and between its head and 35 its base.

The preferred form of my invention comprises also one or more plate springs 9 and 40 10 which are riveted to the body portion 1 in the posterior portions of plate-springs 9 and 10, and the body portion 1 at 11 11 when it is desired to thereby reinforce the stiffness of the resilient plate. The anterior end of 45 the lower spring 9 is farther than the anterior end of the upper spring 10 from the anterior end 2 of the body portion 1 of the resilient plate for gradually reducing the reinforcing effect of the springs upon the plate. 50 While the heel and the ball of the foot are both down and while the weight of the body tends to depress the head of the astragalus, the springs 9 and 10 unite with the plate 1 to resist the depression. As the heel and 55 the instep rise with the weight supported upon the ball of the foot the anterior parts of the plate 1, and the springs 9 and 10 bend. As that bending progresses, first, the shorter and lower spring 9, and next the 60 longer and upper spring 10, is freed at its forward end from the footwear and ceases to reinforce the resilient plate 1. Thus the reinforcing effect of the springs upon the plate is gradually reduced as the heel continues to rise. The anterior ends of the 65

plate springs depress longitudinally prolonged portions of the soft fixed innersole of the footwear and the anterior ends of the depressions would materially aid in preventing the forward slipping of the metallic 70 portion of my invention, if the projection 6 from the heel of the footwear were absent.

The preferred form of my invention comprises a removable cushion or insole 12 which is shaped to conform in outline to the 75 outline of the fixed insole of the footwear, excepting at the places where the side portions of the metallic plate are found. At all such places, and especially at the tongue 8, the cushion is widened sufficiently to cause 80 it to intervene between the side portions of the plate and the foot for the comfort of the patient. The entire cushion or insole is shaped to fit the foot within the footwear.

I claim:

1. In an instep-arch support, a metallic plate having its posterior portion shaped with a raised side more to the rear than the first metatarsal bone and to fit and support the inner and raised side and the lower surface of the tarsal-arch and its anterior portion shaped to underlie the metatarsal-arch and having a substantial tongue forward of the raised side of the tarsal-arch support 90 and rising above the upper edge of the said raised side for location alongside the shaft of the first metatarsal bone between the head and the base of such bone for giving proper position laterally to the forward part of the plate.

2. A resilient plate of an instep-arch support having its posterior portion shaped with a raised side more to the rear than the first metatarsal bone and to fit and support the inner and raised side and the lower surface of the tarsal-arch and its anterior portion curved to fit the lower surface of the foot beneath the metatarsal arch and to extend forwardly to a location anterior to an articulation of a metatarsal bone with its 10 phalanx and having a substantial tongue forward of the raised side of the tarsal-arch support and rising above the upper edge of the said raised side for location alongside the shaft of the first metatarsal bone between the head and the base of such bone for giving proper position laterally to the forward part of the plate.

3. In an instep-arch support, a metallic plate having its posterior portion shaped 120 with a raised side more to the rear than the first metatarsal bone and to fit and support the inner and raised side and the lower surface of the tarsal-arch and its anterior portion shaped to underlie the metatarsal-arch and having a substantial tongue forward of the raised side of the tarsal-arch support, and rising above the upper edge of the said raised side for location alongside the shaft 125 of the first metatarsal bone between the head 130

and the base of such bone for giving proper position laterally to the forward part of the plate, combined with a cushion shaped to fit against the inner surface of the upper of the footwear for maintaining its own proper position longitudinally and laterally of the shoe, and having a sidewise extension for intervention between the foot of the wearer

and the tongue and the side portion of the plate.

In testimony whereof, I affix my signature in the presence of two witnesses.

CLARENCE N. CHILDS.
